Primary Examiner — Darlington Ly*(74) Attorney, Agent, or Firm* — Larry E. Henneman, Jr.;
Baker & Rannells, PA(57) **CLAIM**

The ornamental design for a drill tool, as shown and described.

DESCRIPTION

FIG. 1 is a perspective view of a drill tool, showing my new design;

FIG. 2 is a front elevation view of the drill tool;

FIG. 3 is a rear elevation view of the drill tool;

FIG. 4 is a left-side elevation view of the drill tool;

FIG. 5 is a right-side elevation view of the drill tool;

FIG. 6 is a top plan view of the drill tool; and,

FIG. 7 is a bottom plan view of the drill tool.
